MAGNETIC TAPE TRANSPORT

Ronald E. Loosen, Woodland Hills, Calif., assignor to
Ampex Corporation, Redwood City, Calif., a corpora-
tion of California

Filed Jan. 24, 1966, Ser. No. 959

Term of patent 14 years

(Cl. D26—14)

FIG. 1

FIGURE 1 is a left side, top and front perspective view of a magnetic tape transport, showing my new design with the hinged cover in open position; and

FIGURE 2 is a right side, top and rear perspective view thereof, with the hinged cover in closed position.

Portions of the drawing figures are diagonally lined to indicate transparency.

The dominant features of my new design are shown in solid lines in the drawing.

I claim:

The ornamental design for a magnetic tape transport, substantially as shown and described.
